(57) **CLAIM**

The ornamental design for an icon for a portion of a display screen, as shown and described.

DESCRIPTION

FIG. 1 is a front view of a first embodiment of an icon for a portion of a display screen; and,

FIG. 2 is a front view of a second embodiment of an icon for a portion of a display screen.

The broken lines in the drawings, including the broken line drawing of a portion of a display screen, depict environmental subject matter only and form no part of the claimed design. Unseen portions of the display screen form no part of the claimed design.
